(57) **CLAIM**

The ornamental design for an LED lamp tube, as shown and described.

DESCRIPTION

FIG. 1 is a front perspective view of an LED lamp tube showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a circled portion 9 of FIG. 1; and,

FIG. 10 is an enlarged view of a circled portion 10 of FIG. 1.

The broken lines in the drawings depict portions of the LED lamp tube that form no part of the claimed design. The dash-dot broken lines represent the bounds of the detail views and form no part of the claimed design. The drawings contain symbolic break lines in FIGS. 1-6. The portion between the break lines forms no part of the claimed design.
